(57) **CLAIM**

The ornamental design for a wireless music synchronization (MP3) player-MP3 device, as shown and described.

DESCRIPTION

FIG. 1 is a front view of a wireless music synchronization (MP3) player-MP3 device showing my new design;

FIG. 2 is a back view of the embodiment shown in FIG. 1; FIG. 3 is a top view of the embodiment shown in FIGS. 1-2; FIG. 4 is a bottom view that is opposite of the top view of the embodiment shown in FIG. 3;

FIG. 5 is a left side view of the embodiment shown in FIGS. 1-4;

FIG. 6 is a right side view of the embodiment shown in FIGS. 1-5;

FIG. 7 is an isometric top view of the embodiment shown in FIGS. 1-6; and,

FIG. 8 is an isometric bottom view of the embodiment shown in FIGS. 1-7.
